DESIGN FOR A GOLF CLUB HEAD

George F. Klein, Winnipeg, Manitoba, Canada

Application August 2, 1947, Serial No. 140,683

Term of patent 14 years

(Cl. D34—5)

To all whom it may concern:

Be it known that I, George F. Klein, a citizen of the United States of America and a resident of the city of Winnipeg, Province of Manitoba, Dominion of Canada, have invented a new, original, and ornamental Design for a Golf Club Head, of which the following is a specification, reference being had to the accompanying drawings, forming part thereof wherein:

I claim:

The ornamental design for a golf club head, as shown.

GEORGE F. KLEIN.
